UNITED STATES PATENT OFFICE.

JOAQUIN MORET GONZÁLEZ, OF ORIENTE, CUBA.

INJECTOR.

Application filed March 31, 1926. Serial No. 98,935.

This invention relates to injectors and more particularly to an injector for locomotive boilers.

It is an object of this invention to provide a novel arrangement of the forcing and lifting nozzles which will permit removal of the forcing nozzle without removing the lifting nozzle.

It is a further object of this invention to provide an auxiliary water chamber between the overflow chamber and the water supply chamber, an automatic valve being provided between the auxiliary chamber and the water supply chamber.

It is still another object of this invention to provide a three-way valve for connecting the auxiliary water chamber to the overflow chamber or the overflow outlet.

Other objects will be apparent from the following description of the invention taken in connection with the accompanying drawings in which:

Figure 1 is an elevation, in section, of the preferred form of the invention;

Figure 2 is a longitudinal sectional view of the forcing nozzle; and

Figure 3 is a section taken on the line 3—3 of Figure 1.

Referring to the drawings the body or casing 10 of the injector is provided with usual water inlet 11, steam inlet 12, overflow outlet 13 and delivery outlet 14. The interior of the injector casing is divided into several chambers by the transverse portions

15, 16, 17, 18, thus forming the steam chamber 19, the water supply chamber 20, the auxiliary water chamber 21, the overflow chamber 22, and the discharge chamber 23. In the partition 15 is removably secured the

steam forcing nozzle 24, in which is also removably secured the lifting nozzle 25. The nozzles 26, 27 and 28 are removably secured in the partitions 16, 17 and 18 respectively. The openings in which the nozzles

45 are secured are in alignment and increase progressively in diameter from the discharge end towards the rear end, thus making it possible to remove all of the nozzles from the rear end of the injector. The construction

50 of the discharge and rear ends of the injector and the operating valve 45 is similar to that shown in the patent to Gonzalez, No. 1,571,406, granted February 2, 1926.

The nozzle 24 is threaded as at 24^a and

55 is adapted to be screwed into a threaded aperture in the partition 15. A bridge 24^b within the nozzle 24 is provided with a threaded aperture 24^c for receiving the threaded portion 25^a of the nozzle 25. The bridge 24^b has a number of small steam passages 24^d so that the steam, when the valve 45 is partly open, may pass into the water chamber 20. It is to be noted that the nozzle 25 may be withdrawn from the injector thru the rear end without disturbing the nozzle 24.

60 The valve spindle 32 passes thru the bonnet 31 which is provided with a nut 33 and fluid tight packing 34. Pivoted to the rear end of the valve spindle 32 is an operating handle 35 to which are also pivoted the links 36 and 37. The forward end of the link 36 is pivoted to the injector casing at 38 and the link 37 is pivoted at its forward end to a starting valve spindle 39, to which is attached a valve head 40 adapted to seat against the valve seat 41. The valve operating handle is further provided with a pawl 42 adapted to fit in the groove 43 of the

55 guide 44. The passage of steam thru the steam nozzle 24 is controlled by the valve 45 which is constructed in two cylindrical cup shaped parts, 45^a and 45^b one slidably within the other. The outer part 45^b is threaded on the valve spindle and is provided with a reduced portion 46 in its side wall and an opening 47 thru which the inner part 45^a slides. Each part is provided with a shoulder 48 and the valve is so constructed that the outer part 45^b may be moved rearwardly some distance before the shoulders abut, at which time further rearward movement of the part 45^b causes the inner part 45^a to also move rearwardly, thus opening the passage in the steam nozzle 25.

85 Immediately above the water supply chamber 20 is a passage 51 providing communication between the chambers 20 and 21 thru the opening 52 in the upper wall of the chamber 20. The opening 52 is controlled by a gravity check valve 53 which will open when the pressure within the chamber 21 falls below that in chamber 20.

100 Connecting the auxiliary chamber 21 with the overflow chamber are the passages 54, 55, while the passages 56, 57, connect these chambers with the overflow outlet 13. The three-way valve 58 controls the flow of water thru the passages 54, 55, 56 and 57, it being

obvious that communication between the auxiliary chamber, overflow chamber and overflow outlet may be established by turning the valve 58 to the proper positions. It 5 will be seen that the three-way valve is provided with a squared spindle 59 to which a wrench or handle may be supplied. A spring 60 in the cup-shaped extension 61 of the valve bears against the cup 62 and 10 forces the valve against the packing 63, thus making tight joint for the spindle 59.

The injector is further provided with an overflow check valve 64 and a discharge check valve 65 which operate in the usual 15 manner.

The operation of the injector will be understood from the above description and by referring to the drawings. The valve operating handle 35 is moved rearwardly 20 until the pawl 42 engages the groove 43. In this position the valve 45^b is opened to permit steam to enter the nozzle 26 thru the steam passages 24^a. The valve 40 is still open at this time and the rotary valve 58 25 is turned to provide communication between the auxiliary chamber 21 and the overflow chamber 22. The vacuum created in these chambers lifts water into the supply chamber, auxiliary chamber and overflow chamber. 30 After the flow of water has started the valve handle 35 is pulled back until the valve 45^a uncovers the nozzle 25 and the valve 40 closes passage 57. The overflow valve 64 will now close and the check valve 53 open, due to the reduced pressures in chambers 21 and 22. The chambers 21 and 22 35 may be readily drained when the injector is not in operation, the valve 58 being turned to connect these chambers with the overflow discharge 13. The valve 58 may be turned to connect either or both of chambers 21 and 22 with the overflow discharge 13. Usually 40 when the injector is operating normally, it is not desirable to have the overflow chamber 22 connected with the overflow discharge so the valve is turned as shown in Fig. 1 to connect only the intermediate condensing water chamber 21 with the overflow discharge; but if the delivery check valve 65 45 or overflow check 64 fails to function properly on account of high back pressure, wedging of the valve on its ways or other causes, the three-way valve 58 may be turned to connect the overflow chamber 22 with the overflow discharge 13 to provide a rapid flow of fluid through the apparatus. This rapidly 55 flowing fluid, when started will unseat the disarranged valves and start them into normal operation after which the three-way valve is turned back into position in which it is shown in Figure 1.

Having thus described the invention, what is claimed as new and desired to be secured by Letters Patent is:

65 1. In an injector, a water supply chamber,

an overflow chamber, an intermediate condensing water chamber between said supply and overflow chambers, nozzles extending into each of said chambers, an overflow discharge, and a three-way valve to provide 70 communication between the overflow discharge, overflow chamber and auxiliary chamber.

2. In an injector, a water supply chamber, an overflow chamber, an auxiliary water 75 chamber between said supply and overflow chambers, nozzles extending into each of said chambers, an overflow discharge, and valve means to provide communication between said auxiliary chamber and said overflow discharge when in one position, between said auxiliary chamber and said overflow chamber when in another position and between both of said chambers and said overflow discharge when in a third position. 80

3. In an injector, a water supply chamber, an overflow chamber, an intermediate condensing water chamber between said supply and overflow chambers, an overflow discharge, and a three-way valve disposed 90 adjacent the lowermost portions of said overflow and intermediate condensing water chambers to provide communication between them and the overflow discharge.

4. In an injector, a water supply chamber, an overflow chamber, an auxiliary water chamber between said supply and overflow chambers, an overflow discharge, and valve means disposed adjacent the lowermost portions of said overflow and auxiliary water 100 chambers to provide communication between said auxiliary chamber and said overflow discharge when in one position, between said auxiliary water chamber and said overflow chamber when in another position, and between both of said chambers and said overflow discharge when in a third position. 105

5. In an injector, a water supply chamber, an overflow chamber, and an intermediate condensing water chamber between 110 said supply and overflow chambers, nozzles extending into each of said chambers, and a check valve between said supply and intermediate condensing chambers.

6. In an injector, a water supply chamber, an overflow chamber, an intermediate condensing water chamber between said supply and overflow chambers, an overflow discharge, nozzles extending into each of said chambers, a check valve between said supply and intermediate condensing chambers, and a three-way valve to provide communication between the overflow discharge, overflow chamber, and intermediate condensing chamber. 115 120

7. In an injector, a water supply chamber, an overflow chamber, an auxiliary water chamber between said supply and overflow chambers, an overflow discharge, nozzles extending into each of said chambers, a 130

check valve between said supply and auxiliary chambers, and valve means disposed adjacent the lowermost portions of said overflow and auxiliary water chambers
5 to provide communication between said auxiliary chamber and said overflow discharge when in one position, between

said auxiliary water chamber and said overflow chamber when in another position, and between both of said chambers and said overflow discharge when in a third position.

10 In testimony whereof I hereunto affix my signature.

JOAQUIN MORET GONZÁLEZ.
